UNITED STATES PATENT OFFICE

LEVI LUNDQUIST, OF MIDDLETON, CALIFORNIA

DOOR TEMPLATE

Application filed February 20, 1929. Serial No. 341,521.

This invention has for its object the provision of a simple tool whereby to attain accuracy in the fitting of doors to door openings and the placing of hinges upon doors and door jambs without an experimental setting up of the doors. The invention provides a light, simple and easily manipulated frame which may be fitted within a door opening against the door jambs and upon which are mounted indicators whereby the proper location of the hinge butts may be accurately determined and which frame may be easily fitted to a door to indicate the location of the mating hinge butts. The invention is illustrated in the accompanying drawings and consists in certain novel features which will be hereinafter first fully described and then more particularly defined in the appended claim.

20 In the drawings:

Figure 1 is a front elevation of the device applied to a door frame,

Fig. 2 is a vertical section on the line 2—2 of Fig. 1,

25 Fig. 3 is an enlarged detail perspective view of a portion of one of the gage bars and the parts mounted thereon, and

Fig. 4 is a detail section on the line 4—4 of Fig. 3.

30 In the drawings, the reference numeral 1 indicates a door frame which may be of any desired or approved dimensions and is of the usual construction including a door stop 2.

In carrying out the present invention, there are provided a pair of side or gage bars 3 of such length as to be adapted to rest against door jambs of average height and each of which is equipped at its upper end with an extension bracket 4 whereby its effective

40 length may be increased and the bar adapted for use against jambs of maximum height. The extensions 4 consists of metallic plates bearing against one side of the respective gage bar and having along one edge a flange

45 5 which is adapted to rest against the inner edge of the gage bar 3, as shown clearly in Figs. 3 and 4. At the opposite edge of the extension plate or bracket is formed a tongue 6 which projects past the adjacent edge of

50 the bar 3 to bear against the door stop 2, as

shown in Fig. 2. The lower portion of the tongue 6 is bent inwardly, as shown at 7, whereby to lap around the edge of the gage bar and thereby hold the plate in proper relation to the bar. The plate is adjustably secured to the bar by a bolt 8 carried by the plate and extending through a longitudinal slot 9 in the bar and equipped with a wing nut 10 adapted to be turned home against the bar, as will be understood. The tongue 6 is located at a fixed distance from the upper extremity of the plate 4, as will be understood, and this distance is the same as the distance from the top of the door jamb at which the uppermost hinge is generally located. When the gage bar has been set against the door jamb, the extension 4 will abut the lintel of the door frame and the upper edge of the tongue 6 will indicate the proper location of the upper edge of the hinge butt 70 and the workman may then make a pencil mark upon the door jamb drawn along the upper edge of the tongue 6 so that the position of the hinge will be accurately defined.

At intervals in the length of the gage bar, 75 three plates 11 are mounted upon the edge of the same. These plates correspond in thickness to the clearance desired between the door jamb and the edge of the door, and, when the template is fitted to the door frame, 80 they assume positions between the jamb and the gage bar, as shown in Fig. 1. The top plate 11 is located just below the extension bracket 4 so that it will not interfere with the adjustment of the bracket and it acts with the other plates 11 to assure proper positioning of the template on the door. The middle plate is brought into use when three hinges are to be set and is turned to a right angle 85 with the side of the bar so that the workman, by drawing a line along the upper or the lower edge of the plate may mark the location of the middle hinge. The lowest plate 11 is so located that when it is turned to a right angle to the gage bar, its upper edge 90 will mark the location of the lowest hinge. As only one edge of the door is to be marked, the plates on the other gage bar are left in a longitudinal position on the edge of the bar 95 so that the bar may lay flat when applied to 100

the door, and two gage bars of identical construction are provided to adapt the template to the hanging of doors which swing to the right or those which swing to the left. It is desirable, of course, that the gage bars be arranged in identical relation to the respective jambs and this result is attained by the provision of adjustable braces 12 which are disposed between the bars and are each pivotally attached at its lower end to one of the gage bars, the pivots being located at the same distance from the lower ends of the gage bars. These braces cross each other between the gage bars and are pivotally connected, as indicated at 13. In the upper end of each brace is fitted a set bolt 14 which plays in a longitudinal slot 15 in the respective gage bar and is equipped with a wing nut 16 whereby it may be secured in a set position. When the gage bars are being fitted to a door frame, the braces are relatively loose and their upper ends may move along the slots 15 until the gage bars have been properly placed, whereupon the wing nuts are turned home so as to secure the braces in the positions in which they may have been set, thereby positively securing the gage bars in parallel relation and at such a distance apart as will permit each gage bar to bear closely against the respective door jamb. By providing the gage bars in duplicate, either bar may be used as the gage in a door frame which is to receive only a single door and in any event the braces serve to hold the template firmly within a door frame so that the workman in marking the spots at which the hinges are to be placed is not required to hold the template in place and, consequently, is not apt to shift the same and cause inaccuracy in his markings.

After the door jambs have been properly marked, the template is removed bodily intact from the door frame and one gage bar is then placed against the edge of the door which is to be hung. The turn plates 11, being still at a right angle to the gage bar, by bearing against the edge of the door will serve as guides to insure that the gage bar is placed parallel with the sides of the door and accuracy in the location of the hinge butts is thereby assured. Inasmuch as the gage bars have been adjusted to the door frame with the desired clearance, when the template is placed against the door, any discrepancy between the width of the door and the measurement indicated by the template will at once be apparent, so that any necessary trimming of the door may be effected. Obviously preliminary fitting of the door to the door opening is unnecessary and the frequent lifting of the door is eliminated.

Having thus described the invention, I claim:

A door template comprising a gage bar adapted to bear against a door jamb, and an

extension plate adjustably secured against a side of the bar adjacent an end thereof, said extension plate having a flange along one side edge to bear against the adjacent edge of the bar and being provided on its opposite side edge with a tongue comprising a gage element bearing against and projecting past the respectively adjacent edge of the bar.

In testimony whereof I affix my signature.
